To all whom it may concern:

In the drawings, Fig. 1 is a front elevation of a camera casing showing my new design;

Fig. 2 is an elevation of one side of the camera casing shown in Fig. 1; and

Fig. 3 is an elevation of the opposite side from that shown in Fig. 2.

A view of the camera back is not shown since this portion of the camera is plain and conventional.

I claim:

The ornamental design for a camera casing, as shown and described.
